Ernest J. Swimmer, 229 E. 53rd St., New York, N.Y.

Filed Feb. 18, 1960, Ser. No. 59,444

Term of patent 7 years

(Cl. D34—5)

FIG. 1

FIG. 2

FIG. 3

Fig. 1 is a plan view of the game board showing my new design.

Fig. 2 is a slightly enlarged fragmentary vertical section taken on the line 2—2, Fig. 1.

Fig. 3 is an enlarged perspective view showing one of the projection elements rising from the flat base of the game board.

The bridging accessory shown in broken lines in Figs. 1 and 2 is for illustrative purposes only.

I claim:

The ornamental design for a bridging game board, as shown and described.
